(57) **CLAIM**

The ornamental design for a dry cleaning machine, as shown and described.

DESCRIPTION

FIG. 1 is a perspective view of a dry cleaning machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof showing the state that during operation, the inside light has been lit and thus the user can check the status of dry cleaning through the window of the front door.

The broken lines depict a portion of the interior of the dry cleaning machine forming no part of the claimed design.
